UNITED STATES PATENT OFFICE.

MILTON F. WILLIAMS, OF ST. LOUIS, MISSOURI, ASSIGNOR TO WILLIAMS PATENT CRUSHER & PULVERIZER COMPANY, OF ST. LOUIS, MISSOURI, A CORPORATION OF MISSOURI.

FEED-REGULATOR.

No. 878,847.

Specification of Letters Patent.

Patented Feb. 11, 1908.

Application filed July 15, 1907. Serial No. 383,782.

To all whom it may concern:

Be it known that I, MILTON F. WILLIAMS, a citizen of the United States, residing at St. Louis, Missouri, have invented a certain new and useful Improvement in Feed-Regulators, of which the following is a full, clear, and exact description, such as will enable others skilled in the art to which it appertains to make and use the same, reference being had 10 to the accompanying drawings, forming part of this specification, in which—

Figure 1 is a side elevation of a feeding machine constructed in accordance with my invention; Fig. 2 is a vertical longitudinal 15 sectional view of the machine shown in Fig. 1; and Fig. 3 is a vertical transverse sectional view of said machine.

This invention relates to machines for feeding material to pulverizers or grinding mills 20 and has for its object to provide an automatic feeder of simple construction that can be adjusted accurately to vary the quantity of material which is fed.

Referring to the drawings which represent 25 the preferred form of my invention, 1 designates the hopper of the machine into which the material is dumped, and 2 designates a horizontally disposed reciprocating member that forms the bottom of the hopper. The

30 lower end of the hopper is constructed, as shown in Fig. 2, and the lower portion of the rear wall of the hopper is formed by an inclined slide 3 which can be adjusted to vary the feed opening between the lower edge of 35 the slide and the reciprocating member 2.

The adjustment of this slide 3 is effected by a nut 4 mounted on a stationary screw 5 extending parallel to the slide, said nut being provided with a groove which receives an extension 6 40 on the slide. Movement is imparted to the reciprocating member 2 by toothed segments 7 which mesh with racks 8 on the underneath side of the reciprocating member 2. The segments 7 are secured to a horizontally dis-

45 posed shaft 9 that is journaled in the side walls of a rectangular-shaped casting 10, and at one end of said shaft is a rock arm 11 which is connected by a link 12 to a rock arm 13 on a driven shaft 14, said driven shaft being pro- 50 vided with a pulley 15. The rock arm 11 is provided with an elongated slot 16, and a stud 17, to which the lower end of the link 12 is connected, is adjustably mounted in said slot. The upper end of said link is connected 55 to a stud 18 which projects laterally from a

block that is mounted in a guideway in the rock arm 13 on the driven shaft, said block being adapted to be moved by an adjusting screw 19 mounted in said arm 13 and having its screw-threaded portion extending through 60 a screw-threaded opening in the block. By adjusting the screw 19 the position of the stud 18 relatively to the axis of the shaft 14 will be varied and thus change the degree of movement imparted to the reciprocating 65 member 2 and the degree of movement of said member can also be varied by changing the position of the stud 17 in the slot in arm 11. By having a double adjustment, as above described, I am able to obtain a very 70 fine and accurate adjustment of the reciprocating member and accordingly, can control absolutely the quantity of material that is fed.

One end of the reciprocating member 2 is 75 supported by the segments 7 and the opposite end of said member is supported by rollers 20 on a cross shaft 21 which is also mounted in the side walls of the casting 10. These rollers 20 are provided with flanges 22 80 which engage guides or side pieces on the reciprocating member 2 so as to prevent said member from moving laterally, said guides or side pieces consisting of angle irons 23, the horizontal legs of which extend underneath 85 the reciprocating member 2 and form tracks or wearing surfaces for the rollers 20. The vertical legs of the angle irons 23 extend above the top surface of the reciprocating member and project into guideways at the 90 lower edges of the side walls of the hopper 1, as shown in Fig. 3, thereby preventing the material from spilling or rolling laterally off the reciprocating member 2. These guideways for the vertical legs of the angle irons 23 95 are formed by Z-shaped portions 24 projecting laterally from the lower edge portions of the side walls of the hopper and the lower horizontal legs of these Z-shaped portions are secured to flanges 25 on the casting 10 by 100 means of bolts 26, thereby permitting the entire hopper to be removed easily.

The operation of the feeder will be obvious from the foregoing, the reciprocating movement of the member 2 in one direction carrying a certain quantity of the material out of the hopper and then discharging this material into the hopper of the crusher or grinding mill when the slide moves in the opposite direction. The slide 3 and reciprocating mem- 110

ber 2 can be accurately adjusted so that the quantity of material that is fed can be controlled positively. Moreover, the feeder is so constructed that the parts which receive 5 the greatest wear can be removed and replaced by new ones and thus reduce the cost of maintenance.

Having thus described my invention, what I claim as new and desire to secure by Letters 10 Patent is:

1. A feeder comprising a hopper, a reciprocating member forming the bottom of said hopper, an inclined slide forming a portion of one wall of the hopper and having its lower 15 edge separated from the reciprocating member to form a discharge opening, means for adjusting said slide, oscillating toothed segments that mesh with racks on the reciprocating member, a rock shaft to which said segments are secured, a driven shaft, arms on the rock shaft and on the driven shaft, and a link having its opposite ends adjustably connected to said arms; substantially as described.
2. A feeder comprising a hopper, a reciprocating member forming the bottom of said hopper, angle irons secured to said member and having their vertical legs projecting upwardly outside of the side walls of the hopper, 20 supporting rollers on which the horizontal legs of said angles bear, and flanges on the

rollers for engaging the vertical legs of said angles to prevent lateral movement of the reciprocating member; substantially as described.

3. A feeder comprising a hopper provided at the lower edge portions of its side walls with laterally extending Z-shaped members, a rectangular-shaped casting to which said Z-shaped members are secured, a reciprocating member forming the bottom of the hopper and provided at its side edges with flanges which project upwardly into guideways formed by the Z-shaped members and the side walls of the hopper, an adjustable 45 inclined slide forming the lower portion of the rear wall of the hopper, a rock shaft mounted in the walls of the casting and provided with toothed segments that mesh with racks on the underneath side of the reciprocating member, means for actuating said rock shaft, and means for varying the degree of movement imparted to said shaft; substantially as described.

In testimony whereof I hereunto affix my 55 signature in the presence of two witnesses, this eleventh day of July 1907.

MILTON F. WILLIAMS.
